Carl P. Greenleaf

UNITED STATES PATENT OFFICE.

NICHOLAS STOCK, OF KINGSTON, NEW YORK.

CHAIR-TIP.

1,356,797.

Specification of Letters Patent. Patented Oct. 26, 1920.

Application filed April 10, 1916. Serial No. 90,153.

To all whom it may concern:

Be it known that I, NICHOLAS STOCK, a citizen of the United States, and residing in Kingston, in Ulster county and State of 5 New York, have invented certain new and useful Improvements in Chair-Tips, of which the following is a specification.

The present invention relates to improvements in chair tips, and particularly an improved tip which will be readily removable and changeable, and highly resistant to wear and tear. An object of the invention is to provide such a device in which the tip portion is welded upon the metal attaching 10 portion in such manner that it is impossible for the tip to break off or to be rotatably moved with respect to the attaching member. A further object is to provide such a tip in which the metal parts are so constructed 15 as not to mar the finest floors, should the rubber tip portion become worn away without being detected.

With these and other objects in view, my invention is shown in the accompanying 20 drawings, and will be hereinafter more fully described with reference thereto and finally pointed out in the claim.

In the accompanying drawings:

Figure 1 is a perspective view along the 25 lower end of a chair leg with my improved tip attached thereto,

Fig. 2 is a vertical sectional view thereof,

Fig. 3 is a view of the tip partly in section,

Fig. 4 is a view of the attaching screw 30 partly in section and showing in dotted lines the relation of the screw socket,

Fig. 5 is a side view of the screw socket,

Fig. 6 is a sectional view taken on the line 6-6 of Fig. 4, and

Fig. 7 is a sectional view taken on the line 40 7-7 of Fig. 5.

Similar reference characters indicate corresponding parts throughout the several figures of the drawings.

Referring to the drawings, my invention 45 comprises an attachment member 10 screw threaded at its end 11 and at its other end provided with a bowled head 12 having a plurality of openings 13 therethrough. A 50 rubber tip 14 is molded upon the headed

end of the screw as clearly shown in Figs. 2 and 3, the rubber extending through the openings 13 of the head. This construction positively prevents any loosening or rotary motion of the tip upon the screw. The 55 bowed head retains the rubber intact until entirely worn away, and when worn to such an extent that the head becomes exposed, its surface is such that there is no possibility of marring the floor, or tearing the carpet. 60

A socket member 15 interiorly threaded at its upper end 16 is embedded in a hole 17 bored into the end of the chair leg 18, the outer sides of the socket being fluted as at 19 to prevent any turning motion thereof. The lower end of the socket is flared outwardly as at 20 and is countersunk in the chair leg as clearly indicated in Fig. 2. The screw 10 is threaded in to the socket, and the tip is thereby securely and substantially held in place during use while permitting the ready removal and renewal thereof when desired.

The sides of the openings 13 extending through the thickened portion of the head 75 12 it will be seen have a vertical surface contact with the rubber tip, thereby avoiding any possibility of the head cutting into the rubber.

I have illustrated a preferred and satisfactory form of my invention, but it is obvious that changes may be made therein within the spirit and scope thereof as defined in the appended claim.

I claim:

An improved furniture pad comprising an attachment member having a shank, a convex concave circular head at one end of the shank, integral therewith and coaxial thereto and flaring from the shank and at its interior 80 side concave to the shank to form a bowled circular head, and a single piece cushion member molded upon said end of the shank centrally and coaxially with the shank and bowled circular head, completely inclosing 85 and covering all parts of said circular head, said circular head having substantially circular openings therethrough arranged about the shank and spaced inwardly from the rim of the head, said rim being continuous 90 100

and uninterrupted and said openings having annular flat walls whereby to prevent cutting of said cushion and to support said cushion from vertical and lateral displacement from the head, the exterior side of said bowled circular head and the tip end of the shank being on the same continuous unbroken convex curve.

In testimony that I claim the foregoing as my invention, I have signed my name in presence of two subscribing witnesses.

NICHOLAS STOCK.
